UNITED STATES PATENT OFFICE

RUSSELL E. BENNER, OF MIDDLETOWN, CONNECTICUT, ASSIGNOR TO REMINGTON TYPE-WRITER COMPANY, OF ILION, NEW YORK, A CORPORATION OF NEW YORK

TYPEWRITING MACHINE

Application filed April 29, 1929. Serial No. 359,106.

My invention relates to typewriting or like machines and more particularly to means for detachably mounting the platen in the carriage and for detachably connecting the platen with a platen clutch.

The main object of my invention, generally stated, is to provide improved and highly effective means for detachably mounting a platen in the carriage, and for replacing the platen in the carriage with great accuracy and firmness or freedom from looseness or play in its bearings.

Another object of the invention, generally stated, is to provide highly efficient means of the character specified by which the platen may be readily detached and removed, when desired, without removing the line spacing wheel and platen clutch from the carriage.

A further object of the invention is to provide efficient means whereby the platen, when remounted, will be effectively correlated and centered with reference to the line spacing wheel and platen clutch, and will be firmly and effectively connected with a member of the latter.

A still further object of my invention is to provide a construction such as indicated above which may be readily incorporated in existing machines, such for example as the No. 6 Remington-Noiseless machine, without modifying, or materially modifying, the existing structural features of the line spacing mechanism and the platen clutch mechanism.

To the above and other ends which will hereinafter appear, my invention consists in the features of construction, arrangements of parts and combinations of devices set forth in the following description and particularly pointed out in the accompanying claims.

In the drawings, wherein like reference characters designate corresponding parts in the different views:—

Fig. 1 is an enlarged, detail, fragmentary, longitudinal sectional view taken centrally through the left hand portion of the platen and associated parts; the view showing the parts assembled and the platen mounted in place and connected to the line spacing wheel.

Fig. 2 is an enlarged, detail, transverse sectional view taken on the line 2—2 of Fig. 3

and looking in the direction of the arrows at said line; the view showing the manner of supporting the right hand end of the platen in the carriage.

Fig. 3 is an enlarged, detail, longitudinal 55 sectional view taken through the right-hand end portion of the platen.

Fig. 4 is a view showing in perspective and separated, various parts that enter into the construction.

Fig. 5 is an enlarged, detail, fragmentary view, partly in section, of the left-hand end of the platen and some of the coating parts, shown as they appear when the platen is disconnected from the platen clutch and is about 65 to be removed from the carriage.

Fig. 6 is an enlarged, detail, transverse sectional view taken on the line 6—6 of Fig. 1 and looking in the direction of the arrows at said line.

I have shown my invention in the present instance incorporated in the No. 6 Remington-Noiseless machine, in which said invention may be readily embodied without modifying, or materially modifying, the existing 75 structural features of said machine. It should be understood, however, that the invention is not limited to embodiment in such machine but may be employed in typewriting and like machines generally, wherever found 80 available.

The platen clutch disclosed herein is like that now in use in the #6 Remington-Noiseless machine and is disclosed in the patent to George G. Going, No. 1,595,463, dated Aug. 10, 1926.

In the Remington-Noiseless machine, more so than in other typewriting machines, it is highly essential, where a removable platen is employed, that its replacement, or the replacement of a substitute platen, in the machine shall be effected with the utmost exactness, since the slightest variation in the position of the platen in the carriage may operate to a distinct disadvantage by reason of the pressure imprint of the type actions employed in this machine. It is one of the objects of the present invention, therefore, to provide means for effecting a ready removal 90 and replacement or substitution of a platen 95 100

in such a manner that the replaced or substituted platen will be firmly and accurately seated in the carriage as when originally installed at the factory and will be as firmly 5 and accurately connected with its associated parts as in the original factory installation.

The carriage comprises a cross bar 1 formed with oppositely grooved race-ways 2 to receive anti-friction rollers by which the 10 carriage is supported on the case shift frame. Fixedly connected to the cross bar 1 are end plates 3 and 4, the left-hand end plate 3 being provided with a supporting bearing or bushing 5 riveted in place as indicated at 6.

15 The right-hand end plate 4 on the other hand has an open-mouth bearing 7 formed therein.

The cylindrical platen designated as a whole by the reference numeral 8 comprises a tubular body portion or shell 9, which in 20 the present instance is made of metal although the ordinary wooden core may be employed, if desired. The body portion 9 is surrounded by the usual rubber sheath 10. The right-hand platen head 11 has an inwardly 25 extending circular flange 12 that is received in the right-hand end of the tubular member 9 and is connected thereto with a drive fit. This platen head has a long hub, hollow trunnion or sleeve-like extension 13 which passes

30 through the bearing opening 7 in the end plate 4 of the carriage and extends outward beyond said end plate. Surrounding the hub 13 is bearing sleeve or bushing 14 having a circumferential flange 15 adapted to bear

35 against the outer face of the end plate 4 and limit the inward movement of the bushing. Said bushing is preferably tapered towards its inner end, as indicated at 16, and is undercut within its bore, at 17, to receive a

40 metal ring 18 seated in a circumferential groove 19 in the hub 13, for purposes which will hereinafter appear. When the bushing 14 is moved (within the platen) from right to left in its bearing opening 7, it is automatically

45 centered therein by the tapered portion of the bushing and effects a firm seating of the bushing in the carriage, and prevents the withdrawal of the hub 13 up through the open-mouth of the bearing opening 7. When, 50 however, the platen is shifted to the right the ring 18 causes the bushing 14 to be carried to the right out of the bearing opening 7, and the hub 13, which is smaller in diameter than the mouth of the bearing opening 7, may 55 then be lifted up out of such opening.

A finger wheel 20 has a hub 21 that surrounds the hub 13 and is secured thereto by two set screws 22. The inner end of the hub 21 abuts the outer end of the bushing 14 and 60 prevents a displacement thereof along the hub 13 to the right when the platen is fixed against longitudinal displacement.

A spindle or rod 23 extends through the bore of the hub 13 and is squared at its outer 65 end, as indicated at 24. The outer end of this

spindle is tapped with an internal thread, at 25, to receive a headed screw 26. A bearing member 27 has a square bore 28 to fit the squared outer end 24 of the spindle, so that the member 27 and the spindle 23 are connected to turn together. Two oppositely disposed depressions or pivot bearings 29 are provided in the outer side of the member 25 to receive square pivots 30 on a flat semi-circular finger piece 31. This pivotal connection 75 between the spindle 23 and the finger piece 31 connects the two, so that the finger piece is effective, when in operative position, to turn the spindle in the hub 13 and also enables the finger piece to be turned on its pivots 30 from its operative position shown in dotted lines in Fig. 3, to the inoperative position, shown in full lines in the same figure. When the finger piece is in the expanded, dotted-line position it may be employed to turn the spindle 23 independently of the platen but when not in use may be folded to a compact position adjacent to and parallel with the finger wheel 20. By reason of this folding of the finger piece 31, the machine may be received in the 80 standard packing case now employed to ship the machines.

In order to retain the finger piece 31 against accidental displacement from either of the said positions to which it may be shifted, I have provided a spring washer 32 that bears against one pair of flat faces or another of the square pivots 30 and thus retains the finger piece in either of the said pivotal positions to which it may be shifted. An outer retaining member 33 has a reduced shank 34 which extends through the central opening in the spring washer and is received in the central recess 35 in the member 27, and bears against said member and holds it against the shoulder 36 on the spindle 23, formed at the junction between the squared and cylindrical portions thereof. The shank 34 of the retaining member 33 also constitutes a bearing for the free ends of the pivots 30 and prevents an axial displacement of the pivots 30 in their bearings 29. The screw 26, hereinbefore referred to, has its head seated in a countersunk opening in the bearing member 33 and holds the associated parts assembled.

Surrounding the spindle 23 within the platen is a collar 37 held fast to the spindle by a pin 38. This is to enable the spindle when disconnected at its inner end to receive a limited outward movement in the platen without, however, permitting the spindle to be detached from the platen.

The inner end of the spindle 23 is received in an opening in a connecting member 39, and is fixed to said member by a pin 40. The member 39 has a headed portion 41 adapted to bear through intermediate washers 42 against a chuck or clamping member, designated as a whole by the reference numeral 43. The outer end of the connecting member 39 has an 130

internal screw thread 44 which coacts with the threaded, reduced end 45 of a fixed projection on a disk-like clutch carrying section or part 46 on which the line spacing wheel or ring 47 is mounted.

To the left of the thread end 45, the projection on the member 46 is squared at 48 to coact with the four clamping jaws 49 of the chuck 43, said jaws being separated by slits

10 50. The outer surface of each jaw 49 is beveled at 51 to provide a cam face adapted to coact with a corresponding cam face 52 on the interior of the left-hand platen head 53, secured with a drive fit in the left-hand 15 end of the platen shell 9.

The platen head 53 also has a cylindrical bearing portion 54 in which a disk-like portion 55 on the chuck is received, supported and adapted to slide longitudinally of the 20 platen. This platen head also has a cylindrical bearing portion 56 in which the outer segmental surfaces 57 of the chuck jaws are received and adapted to slide. In order to prevent the chuck 43 from turning relatively 25 to the platen head 53 I provide a pin 58 that projects to the left from the disk-like portion 55 of the chuck, and is received and slides in a bearing hole 59 that extends through the platen head.

30 The platen head 53 is further provided with a cylindrical, reduced bearing portion or hollow trunnion 60 adapted to be received in the bearing bushing 5 secured to the end plate 3 of the carriage. The inner surface of the 35 bearing portion 60 receives, when the parts are assembled, a cylindrical bearing portion 61 on the member 46, whereas a larger bearing portion or trunnion 62 on the member receives a bearing in the bushing 5. Thus it 40 will be seen that the platen and the member 46 are both supported and aligned in the same bearing 5.

So far as the present invention is concerned 45 any suitable platen clutch mechanism may be employed, and from certain aspects of my invention it is not essential that platen clutch mechanism be employed, in which instance the member 46 may be regarded merely as an element to which the line spacing wheel is 50 fixed or connected. However, in practice I prefer to employ platen clutch mechanism such as is disclosed in the Going patent hereinbefore referred to, as it lends itself very readily without any material change to use 55 in connection with the devices of my invention for detachably mounting the platen in such a manner that the platen may be detached from the machine independently of line spacing wheel and the clutch mechanism.

60 In describing the platen clutch mechanism I will only briefly refer to it, so that a sufficient understanding of it may be arrived at for the purposes of the present invention.

The inner side of the line spacing wheel 65 or ring 47 is provided with fine teeth 63 with

which radially sliding pawls 64 are adapted to engage. These pawls slide in radial grooves or ways 65 in the member 46. A coiled compression spring 66 coacts with all three pawls and tends to disengage them 70 from the teeth 63. Three plungers 67 are guided in slots 68 in a block 69 held with a drive fit in a recess in the center of the member 46. These plungers also move in registering ways 70 in a spindle 71 in which 75 are also contained expansion springs 72 which force the plungers to the right and cause the cam faces 73 thereon to force the pawls 64 against the force of the spring 66 into engagement with the teeth 63, thus locking 80 the line spacing wheel and the platen to turn together.

A finger wheel 74 is connected to the spindle 71 by a set screw 74a, whereas the spindle has a splined connection with a bearing sleeve 75 riveted to a cover plate 76 which in turn is fixed to the member 46 by screws 77. The inner end of the spindle 71 carries a ring 78 that overlaps the plungers 67 and moves them to the left to release the clutch 90 pawls when the finger wheel 74 is pulled to the left.

A bracket 79 secured to the carriage coacts with the bearing sleeve 75 to provide additional support therefor. A collar 80 surrounds said bearing sleeve inside the upright arm of the bracket 79, and bears at one edge against said arm. A set screw 81 holds the collar in place. The function of this collar is to prevent the part 46, and the various 95 members connected thereto, from being withdrawn from the supports 5 and 79 when the platen is detached therefrom, as shown in Fig. 5.

From what has been said it will be understood that when the platen clutch is released, by pulling out on the finger wheel 74, the platen may be turned by either of the finger wheels 20 or 74 independently of the line spacing wheel 47, which at this time is held 100 against movement with the platen by the usual spring-pressed roller detent 82. When, however, the clutch is closed the line spacing wheel and platen are locked to turn together.

Now in order to detach the platen, the 105 finger piece 31 is first shifted to effective position shown in dotted lines in Fig. 3. It is then turned in an anti-clockwise direction, as the parts are viewed from the right-hand end of the platen. The effect of this is to unthread the member 39 and disconnect it from the member 46. The platen with the parts carried thereby are then free to be shifted to the right, carrying the bushing 110 115 120 125 130 135 140 145 150 155 160 165 170 175 180 185 190 195 200 205 210 215 220 225 9585 9590 9595 9600 9605 9610 9615 9620 9625 9630 9635 9640 9645 9650 9655 9660 9665 9670 9675 9680 9685 9690 9695 9700 9705 9710 9715 9720 9725 9730 9735 9740 9745 9750 9755 9760 9765 9770 9775 9780 9785 9790 9795 9800 9805 9810 9815 9820 9825 9830 9835 9840 9845 9850 9855 9860 9865 9870 9875 9880 988

and the platen is then shifted further to the right to entirely clear it of the projections 45 and 48, and thus remove the platen from the carriage, leaving the platen clutch, 5 line spacing wheel and finger wheel 74 mounted in place on the carriage and held against displacement therefrom by the collar 80.

In the act of unthreading the member 39 from the member 46, the head 40 is shifted 10 to the right releasing pressure on the chuck 43 so that its jaws 49 may spring away and be released from clamping engagement with the parts 48 with which they were forced by the camming action exerted on the jaws by 15 the cam 52 on the platen head 53.

The platen is mounted in place by reversing the operations referred to above. When a threaded connection is effected between the members 39 and 46 a tightening of such connection causes the jaws of the chuck to bear 20 with force on the part 48, due to the camming action on the jaws 49 of the cam face 52. This results not only in firmly clamping the connected parts together, but in properly 25 centering and firmly holding the platen against displacement relatively to the bearings on the carriage and the parts which are allowed to remain on the carriage, but which are to be connected with the platen, such as 30 the line spacing wheel and platen clutch.

From the foregoing description it will be understood that I have provided highly effective means for the purposes set forth, which may be assembled without difficulty, 35 and which allows a platen of one character, such for example as a platen which carries card clamping means, to be substituted for another and different character of platen, such as a standard platen not provided with 40 special card clamping means.

Various changes may be made in the construction, and parts thereof may be employed without others, without departing from my invention as it is defined in the accompanying 45 claims.

What I claim as new and desire to secure by Letters Patent, is:

1. The combination of a carriage, a cylindrical platen, and means for detachably mounting the platen in the carriage comprising means that enable the platen to be removed from its bearings only by first effecting a longitudinal displacement of the platen in the carriage, a part that remains fixed 50 against removal with the platen from the carriage, and a tie rod detachably connected with said part and the detachment of which rod therefrom is necessary to afford a longitudinal displacement of the platen in the carriage.

2. The combination of a carriage, a cylindrical platen, and means for detachably mounting the platen in the carriage comprising means that enable the platen to be removed from its bearings only by first effect- 55

ing a longitudinal displacement of the platen in the carriage, a part that remains fixed against removal with the platen from the carriage, a tie rod, a threaded connection by which said tie rod may be detachably connected with said part and the detachment of which rod therefrom is necessary to afford a longitudinal displacement of the platen in the carriage, a finger piece outside of the platen and operatively connected to said tie rod to turn it, and means that enable said finger piece to be folded to a compact position when not in use. 70 75

3. The combination of a carriage, a cylindrical platen, and means for detachably mounting the platen in the carriage comprising means that enable the platen to be removed from its bearings only by first effecting a longitudinal displacement of the platen in the carriage, a platen clutch that remains fixed against removal with the platen from the carriage, and a tie rod detachably connected with a member of said platen clutch and the detachment of which rod therefrom is necessary to afford a longitudinal displacement of the platen in the carriage. 80 85 90

4. The combination of a carriage, a cylindrical platen, and means for detachably mounting the platen in the carriage comprising means that enable the platen to be removed from its bearings only by first effecting a longitudinal displacement of the platen in the carriage, a part that remains fixed against removal with the platen from the carriage, a tie rod, a threaded connection by which said tie rod may be detachably connected with said part and the detachment of which rod therefrom is necessary to afford a longitudinal displacement of the platen in the carriage, a finger piece outside of the platen and operatively connected to said tie rod to turn it, means that enable said finger piece to be folded to a compact position when not in use, and means for holding said finger piece against accidental displacement from either its position for use or from its folded compact position. 95 100 105 110 115

5. The combination of a carriage, a cylindrical platen, and means for detachably mounting the platen in the carriage comprising means that enable the platen to be removed from its bearings only by first effecting a longitudinal displacement of the platen in the carriage, a part that remains fixed against removal with the platen from the carriage, a tie rod detachably connected with said part and the detachment of which rod therefrom is necessary to afford a longitudinal displacement of the platen in the carriage, a chuck adapted to clamp or engage said part, and means for freeing said chuck from such engagement when said tie rod is being disconnected from said part. 120 125 130

6. The combination of a carriage, a cylindrical platen, and means for detachably 130

mounting the platen in the carriage comprising means that enable the platen to be removed from its bearings only by first effecting a longitudinal displacement of the platen 5 in the carriage, a part that remains fixed against removal with the platen from the carriage, a tie rod, a threaded connection by which said tie rod may be detachably connected with said part and the detachment 10 of which rod therefrom is necessary to afford a longitudinal displacement of the platen in the carriage, a finger piece outside of the platen and operatively connected to said tie rod to turn it, a chuck actuated to clamp or 15 engage said part when the tie rod is threaded into place and to free itself from said part when the tie rod is threaded away from said part.

7. The combination of a carriage, a cylindrical platen, and means for detachably mounting the platen in the carriage comprising a carrier for the line spacing wheel, which carrier and line spacing wheel remain fixed against removal with the platen from the carriage, a chuck carried by the platen, a tie rod carried by the platen and having a threaded connection with said carrier and also operatively connected to said clutch to control the opening and closing thereof.

8. The combination of a carriage, a cylindrical platen, and means for detachably mounting the platen in the carriage comprising a member fixed against removal with the platen from the carriage, a chuck carried by the platen and adapted to engage said member, a tie rod carried by said platen and having a threaded connection with said member and also operatively connected with said clutch to control the opening and closing 35 thereof, and a finger piece on said tie rod by which it may be turned independently of the platen.

9. The combination of a carriage having end plates, a cylindrical platen, bearings for 45 the platen in said end plates, one of said bearings being a cylindrical bearing in which a bearing member on the platen is received and removed by an endwise movement of the platen, the other bearing being formed by 50 an open-ended slot from which a bearing member on the platen is displaced endwise before the platen hub can be lifted out of the open-ended slot, a finger piece carried by the platen, and means controlled thereby for 55 holding the platen against endwise displacement in its bearings.

10. The combination of a carriage having end plates, a cylindrical platen, bearings for the platen in said end plates, one of said 60 bearings being a cylindrical bearing in which a bearing member on the platen is received and removed by an endwise movement of the platen, the other bearing being formed by an open-ended slot from which a bearing 65 member on the platen is displaced by an end-

wise movement of the platen before the platen hub can be lifted out of the open-ended slot, a part which is supported in and fixed against removal from said cylindrical bearing, and a tie rod which extends through the 70 platen and is detachably connected to the said part.

11. The combination of a carriage having end plates, a cylindrical platen, bearings for the platen in said end plates, one of said bearings being a cylindrical bearing in which a bearing member on the platen is received and removed by an endwise movement of the platen, the other bearing being formed by an open-ended slot from which a bearing 75 member on the platen is displaced endwise before the platen hub can be lifted out of the open-ended slot, a part which is supported in and fixed against removal from said cylindrical bearing, a chuck in the platen, and 80 means for opening and closing said chuck on said part.

12. The combination of a carriage having end plates, a cylindrical platen, bearings for the platen in said end plates, one of said bearings being a cylindrical bearing in which a bearing member on the platen is received and removed by an endwise movement of the platen, the other bearing being formed by an open-ended slot from which a bearing 90 member on the platen is displaced endwise before the platen hub can be lifted out of the open-ended slot, a part which is supported in and fixed against removal from said cylindrical bearing, a tie rod which extends through the 95 platen and is detachably connected to the said part, a chuck in the platen, and means controlled by said tie rod for opening and closing said chuck.

13. The combination of a carriage having 105 end plates, a cylindrical platen, bearings for the platen in said end plates, one of said bearings being a cylindrical bearing in which a bearing member on the platen is received and removed by an endwise displacement of the 110 platen, the other bearing being formed by an open-ended slot from which a bearing member on the platen is displaced endwise before the platen hub can be lifted out of the open-ended slot, a tapered bearing sleeve that 115 surrounds a hub of the platen and when the platen is in place receives a bearing in the open-ended slot and prevents the said hub from being lifted through the open mouth of the bearing, and releasable means for holding 120 the platen against endwise displacement in its bearings.

14. The combination of a carriage having end plates, a cylindrical platen, bearings for the platen in said end plates, one of said bearings being a cylindrical bearing in which a bearing member on the platen is received and removed by an endwise displacement of the platen, the other bearing being formed by an open-ended slot from which a bearing mem- 125

ber on the platen is displaced endwise before the platen hub can be lifted out of the open-ended slot, a tapered bearing sleeve that surrounds a hub of the platen and when the platen is in place receives a bearing in the open-ended slot and prevents the said hub from being lifted through the open mouth of the bearing, and releasable means for holding the platen against endwise displacement in its bearings, said releasable means comprising a part which is supported in and fixed against removal from said cylindrical bearing, and a hand actuated tie rod which extends through the platen and has a detachable threaded connection with said part.

15. The combination of a carriage, a cylindrical platen, and means for detachably mounting the platen in the carriage comprising bearings on the carriage for the platen and from which the platen can be removed only by effecting an initial longitudinal displacement of the platen in said bearings, one of said bearings being provided by an open-ended bearing slot, and a tapered bearing sleeve carried by the platen and providing a bearing therefor, said sleeve adapted to be seated and find a bearing in said open-ended bearing slot and when thus seated to prevent a removal through the open-mouth 30 of the bearing slot but when displaced from said bearing by a longitudinal displacement of the platen enables the removal of a supporting portion of the platen through said open-mouth of the bearing slot.

35. The combination of a carriage, a cylindrical platen, and means for detachably mounting the platen in the carriage comprising a rotative part that remains fixed against removal from the carriage and to 40 which the platen may be attached and from which it may be detached without removing said rotative part from the machine, a chuck carried by the platen, and means for closing said chuck on said rotative part when the platen is in place and for disengaging the chuck from said rotative part preliminary to a removal of the platen from the carriage.

45. The combination of a carriage, a cylindrical platen, a platen clutch that remains fixed against removal from the carriage, and means for detachably mounting the platen in the carriage for removal independently of said clutch, said means comprising a chuck carried by the platen, and means for closing said chuck on a member of said platen clutch to hold the platen and said clutch member united and to free said chuck preliminary to a removal of the platen independently of said platen clutch and while the latter remains in the carriage.

60. The combination of a carriage, a cylindrical platen, a line spacing wheel, a carrier for the line spacing wheel, which carrier and line spacing wheel remain fixed against removal with the platen from the carriage,

and means for detachably mounting the platen in the carriage for removal independently of said line spacing wheel and carrier, said means comprising a chuck carried by the platen, and means for closing the chuck on said carrier to connect the platen and carrier and for opening said chuck to release the connection and permit the removal of the platen independently of said carrier and line spacing wheel.

65. The combination of a carriage, a cylindrical platen, a rotative member fixed against removal from the carriage, and means for detachably mounting the platen in the carriage for removal therefrom independently of said rotative member, said means comprising a chuck carried by the platen and adapted to engage said member, and means extending outside of the platen for controlling the opening and closing of said chuck.

70. The combination of a carriage, a cylindrical platen, a rotative member fixed against removal from the carriage, and means for detachably mounting the platen in the carriage for removal independently of said rotative member, said means comprising a chuck carried by the platen and adapted to engage said member, a platen head having a cam with which the jaws of said chuck coact to control the opening and closing of the chuck on said member, means for controlling a longitudinal shifting movement of the chuck in the platen and thereby bring about the opening or closing of the chuck through the action of said cam thereon, means for disconnecting said controlling means from the chuck, and means for affording an axial displacement of the platen after such disconnection has been effected.

75. The combination of a carriage, a cylindrical platen having a supporting portion, and means for detachably mounting the platen in the carriage comprising bearings on the carriage for the platen and from which the platen can be removed only by effecting an initial longitudinal displacement of the platen in said bearings, one of said bearings being provided by an open-ended bearing slot, a tapered bearing sleeve carried by the platen and providing a bearing therefor, said sleeve adapted to be seated and find a bearing in said open-ended bearing slot and when thus seated prevents removal of said supporting portion of the platen through the open-mouth of the bearing slot but when displaced from said bearing by a longitudinal displacement of the platen enables the removal of said supporting portions of the platen through said open-mouth of the bearing slot, a tie rod and associated connections that prevent a longitudinal displacement of the platen in its bearings, and a member connected with the platen and which bears against said sleeve when the tie rod is in place and prevents a displacement of the

sleeve from the bearing slot in which it is seated.

22. The combination of a platen having a hub, a carriage having end plates, a line spacing wheel carried by and permanently mounted for rotative movement on one of said end plates, bearings for the platen in said end plates, one of said bearings being a cylindrical bearing in which a bearing member on the platen is received and removed by an endwise movement of the platen, the other bearing being formed by an open-ended slot from which a bearing member on the platen is displaced endwise before the platen hub can be lifted out of the open-ended slot, a finger piece carried by the platen, and means controlled thereby for holding the platen against endwise displacement in its bearings and for detachably connecting the platen to said line spacing wheel.

Signed at Middletown in the county of Middlesex and State of Connecticut, this 24th day of April, A. D. 1929.

RUSSELL E. BENNER.
